JOHN S. LONDON, OF PORT JERVIS, NEW YORK.

AUTOMATIC TRAIN CONTROL.

Application filed May 12, 1926. Serial No. 108,609.

This invention relates to improvements in automatic train control and has particular reference to a reduction governor for automatic brake valves.

- 5 The primary object of the invention resides in a suitable automatic mechanism for use in connection with the engineer's brake valve, which automatically operates the valve in a manner similar to the engineer's manual 10 operation of the same, that is, on the split reduction principle wherein a predetermined amount of air pressure is released to move the air brakes to a set position, and after which the emergency pressure is applied in 15 timed relation to the initial pressure to set up the necessary braking action for bringing the train to a quick stop, in the event that the train should accidentally enter a charged block.
- 20 Another object of the invention is to provide an automatic mechanism operable to automatically apply the air brakes of a train, and which prevents the manual operation of the brake valve to decrease the air pressure, 25 but which permits the manual movement of the valve in a direction to increase the air pressure if so desired. It will, therefore, be seen that when the automatic means is operated, it is beyond the control of the 30 engineer to release the brakes until such time as it is safe to proceed.

Another object of the invention is to provide automatic mechanism which may be installed on trains now in use without necessitating radical changes in construction to the equipment now employed for manually applying the brakes, thus making the cost of installation relatively inexpensive.

With these and other objects in view, the 40 invention resides in certain novel construction and combination and arrangement of parts, the essential features of which are hereinafter fully described, are particularly pointed out in the appended claims, and are 45 illustrated in the accompanying drawing, in which:—

Figure 1 is a diagrammatic view of an air brake applying apparatus with my automatic mechanism applied thereto.

50 Figure 2 is a vertical longitudinal sectional view through the automatic brake valve and governor.

Figure 3 is a horizontal sectional view on the line 3—3 of Figure 2.

Figure 4 is a detail vertical sectional view 55 on the line 4—4 of Figure 3.

Figure 5 is a horizontal sectional view on the line 5—5 of Figure 2.

Referring more particularly to the drawings, the reference numeral 10 designates 60 the main air reservoir of an air brake system, 11 the air compressor for charging the main reservoir to a predetermined pressure, and for example, we shall consider that the maximum air pressure in the tank is one 65 hundred and ten pounds. The engineer's brake valve is shown in its entirety as at 12 and includes a high pressure cylinder 13 and a low pressure cylinder 14 within which the respective pistons 15 and 16 are adapted 70 to reciprocate. The said pistons are connected by a rack bar 17 having a series of teeth 18 on one edge thereof and a series of teeth 19 on the opposite edge. Normally, 75 the high pressure cylinder 13 is charged with an air pressure of one hundred and ten pounds, or that equal to the air pressure in the main reservoir, and which cylinder is supplied with air from the main reservoir through a pipe line 20 within which the 80 usual electro-pneumatic valve 21 is arranged. An equal amount of pressure is maintained behind the pistons 16 in the low pressure cylinder 14 by reason of a pipe 22, which 85 enters the cylinder rearward of the piston 16 and which has communication with the passage 23 through which air from the main reservoir and cylinder is controlled by an automatic rotary valve 24 having an arcuate 90 shaped slot 25 therein for bridging the passage 23 and the entrance of the pipe 22, whereby to establish communication therebetween.

The rotary valve 24 has its peripheral edge provided with a segment of gear teeth 95 26 for meshing engagement with the series of teeth 18 on the rack bar for imparting rotary motion to the valve upon movement of the rack bar in opposite directions.

From the description thus far, it will be 100 seen that when the electro-pneumatic valve is operated by reason of a train entering a charged block, the solenoid therein is de-energized causing the air in the high pres-

sure cylinder to exhaust to the atmosphere through the port 27 in the casing of said electro-pneumatic valve. As the pressure in the high pressure cylinder is exhausted, the air pressure in the low pressure cylinder forces the piston 16 to the dotted position shown in Figure 3 of the drawings, until the piston 16 passes the port 29 therein, whereupon the pressure is exhausted through the pipe 30, and such pressure is lost therein due to the closing of the port 23 by the valve 24, thus leaving the piston 16 against the spring 31 for a purpose presently to be set forth.

15 Simultaneous to the closing of said port 23, a second port 32 is opened through an arcuate slot 32' in valve 24 to afford communication between the port 32 and the pipe 33 leading from the equalizing reservoir 34, 20 to allow an air reduction of approximately ten pounds therefrom to set the brakes by permitting the exhaust of such pressure through the port 35 to the atmosphere. The manner and mechanism employed in 25 conjunction with the equalizing reservoir for applying such braking is well known and therefore deemed unnecessary to describe. Upon continued rotation of the valve 24, said ports 32 and 35 will be closed, but the 30 reduction effected by the open period of the same causes a continued ten pound application of brakes until additional or full brake pipe pressure is applied in a manner set forth hereinafter.

35 Intermediate the opening and closing of the ports just described, a slot 36 opens communication between a port 37, supplied with the main reservoir pressure, and a port 38 to deliver pressure for a predetermined 40 period through a pipe 39 to a third vertically disposed cylinder 40 which is mounted between the cylinders 13 and 14. A piston 41 is slidably mounted within said cylinder 40 and is connected to a vertical shaft 42 provided with a key 43. Said shaft and key are slidably vertically and rotatable within a sleeve-portion 44 of the main rotary valve actuator 45 for a purpose to be presently described. The sleeve 44 is slotted as at 46 50 to receive the key of a gear segment 47 adapted for mesh with the teeth 19 of the rack bar 17 for imparting rotation to the sleeve and actuator 45. The slot 46 extends into the body of the actuator to receive the key 43 when the same has been depressed by the downward movement of the piston 41 55 when the ports 37 and 38 are opened in the manner set forth.

60 The actuator 45 is provided with a bearing shoulder 48 for supporting an externally square collar 49 adapted to receive the square opening in the hub 49' of the engineer's control handle 50, and said collar is slotted as at 51 to receive the portion of the key 43 which 65 extends through the aligned slot 46 to opera-

tively connect said control handle with the usual main rotary valve 52 for manual or automatic operation thereof.

From the description thus far, it will be seen that when the rotary valve 24 is in the position shown in full lines in Figures 2 and 3, the control handle is in operative connection with the main rotary valve 52 and may be manipulated manually independent of the automatic means, to apply the service or emergency brakes in a "clear" block wherein the electro-pneumatic valve rests in a condition to permit the main reservoir pressure to remain in the cylinder 13.

At a point slightly in advance of the termination of the first stroke of piston 16, as far as the spring 31, a slot 54 in the rotary valve 24 is brought into registry with a duct or port 55 which also supplies the main reservoir pressure through said slot 54 to 85 a port 56 and is led through a pipe 56' to what I term the "split reduction governor" 57, the function of which will be presently described.

90 The main rotary valve 52 is of the usual construction wherein rotation either manually or automatically causes registration with the various branch conduits 58 which are in communication with the pipe 59 to supply the main reservoir pressure in various stages to afford the various brake applications from "running" position to "holding" position, "service", etc., up to and including "emergency". Mounted within the 95 brake valve housing 12 is the equalizing piston 60. This piston is normally in the position shown in full lines in Figure 2 and the chamber 61 lying below said piston carries a normal air pressure of one hundred and ten pounds through the medium of the port 100 62 which at this time is in communication with the train line pressure through the pipe 62'. A normal pressure of one hundred and ten pounds is also maintained in the chamber 105 63 above the piston 60, through the connection 64 tapped from the main line 65, leading from the equalizing reservoir 34. A duct 66 is in communication with the connection 64 and the main rotary valve 52, whereby the 110 same may exhaust ten pounds from the equalizing reservoir by manual control to effect the usual reduction to set the brakes in a manner similar to the automatic method previously set forth. The pressures below and 115 above the piston 60 are isolated from each other and therefore serve to hold the piston 120 in the normal position shown.

125 The shank 67 of the piston 60 is bevelled at its lower end as at 68 for co-action with a seat 69 to provide a valve for controlling the exhaust from the chamber 61, due to various conditions and variations in pressures, as will be set forth. A rod or stem 70 is suitably secured to the lower extremity 130 of the piston shank 67, and extends down-

wardly into the governor 57 and is provided with an upper valve disk 71 for co-action with a seat 72 in the governor casting and a lower valve disk 73 for co-action with a similar seat 74. A disk 75 is secured to the lower extremity of the stem 70 to coact with an expansible spring 76 for normally exerting a slight upward pressure to substantially neutralize the piston to normally "float" between the pressures in the chambers 61 and 63. The gravity exerted on the valve 71 through slight weight of the piston thereon is sufficient to hold the valve closed against pressure from the pipe 56' by reason of the normal pressure in the chamber 63.

It might be here stated that when the brake valve is being manually controlled in a "clear" block, should the emergency brakes be needed, the engineer moves the brake handle to a predetermined point to set the brakes and then allows a lapse of approximately ten seconds to permit the brakes to effectively receive the emergency application. Therefore, it is one of the objects of the present invention to accomplish this same desired split-reduction, automatically, and it will be seen from the following description, the manner in which the reduction governor 57 attains this end.

As previously set forth, the ports 55 and 56 are opened to deliver main reservoir pressure to the governor 57 slightly in advance of the completion of the first half stroke of the piston 16, and such action occurs after the port 35 has begun to exhaust pressure from the equalizing reservoir 34. During such exhaust, the main reservoir pressure reaches the port 55 through the pipe 59, which enters the compartment about the rotary valve 52 and then passes through the vertical port 23 as indicated by the arrows in Figure 4 of the drawings from where it enters the slot 25 in the valve 24, which slot bridges the ports 22 and 23. The pressure is relieved from the chamber 63, to cause the ten pound reduction previously described, to actuate the usual triple valve (not shown) to set the brakes, and it will be seen that such release of pressure in said chamber will cause the piston 60 to rise, due to overbalancing by the greater pressure in the chamber 61, and lift the valve 71 from its seat to exhaust any standing pressure in the line 30 through the port 78 and closes the valve 73 simultaneous to the opening of the port 56 by the rotary valve 24 whereupon pressure passes through the pipe 56' to the lower chamber of the governor and is there held while the piston 60 is up.

Upon such upward movement of the piston 60, the valve 68 on the piston shank will permit exhaust of pressure through the duct 77 in the neck of the governor and through

exhaust opening 78 to reduce pressure in the chamber 61 equal to the amount discharged from the chamber 63, and equalize the piston 60 to depress the same to original position and close the valve 71 and open the valve 73.

Thereupon, the pressure from the pipe 56' will pass valve 73 and through pipe 30 to the central port 29 of the cylinder 14 and force the piston 16 to the left for the remainder of its stroke against the spring 31, the normal function of which is to position said piston at the proper point to remain in position to receive its second impulse, immediately upon the termination of pressure thereto on its first movement as specified.

Upon such second movement of the piston 14 to the left, the teeth 19 of the rack bar 17 will engage the gear segment 47 to rotate the same together with the key 43 through the medium of its connection therewith by the slot 46 of the sleeve 44. As previously explained, the key 43, at the time rotation is imparted thereto, is depressed by continuous pressure in the cylinder 40 upon piston 41, and lies in the slot in the body of the actuator 45, below the shoulder 48 thereof, thus disconnecting the control handle 50 from manual manipulation of the main rotary valve 52 in a clockwise direction as the key is depressed as stated, and rotated in a counter-clockwise direction to increase the brake application to emergency, when the train runs into a restricted block.

It will therefore be seen that the split reduction governor 57, accomplishes the two-stage braking automatically in the same manner as an engineer manually effects such application.

The ports 37 and 38 are so timed by the valve 24, as to close immediately after the gear 47 has rotated the key a slight distance in its depressed position below the shoulder 48, and pressure is therefore relieved through the port 79 of the cylinder 40 to permit the spring 79' to force the key 43 upward against the underface of the collar 49 of the control handle 50. It will be seen that as the piston 16 continues its movement to the left, due to the pressure remaining "on" until reset as hereinafter explained, the key will continue on its rotation increasing brake application, but should the engineer be in possession of his full mental faculties and desire to manually advance the rotary valve 52 to an emergency position at a more rapid rate than the same is moving automatically, he may do so, for as stated, the pressure has been released in the cylinder 40 and the spring is forcing the key 43 upwardly and will snap into the slot 51 of the collar 49 of the control handle 50 to operatively connect the same with the main rotary valve 52.

The engineer cannot, however, release the

brakes while in a restricted block, for if the handle 50 is even brought to a position to receive the key and then turned back in a clockwise direction, the valve 24 will rotate 5 rearwardly only until the slot 36 again opens the ports 37 and 38, whereupon pressure will again pass to the cylinder 40 and cause depression of the key in the manner set forth, and due to continuous pressure on the 10 piston 16, the same will again drive the key counter-clockwise to deliver further application of brakes until the same have received the emergency application and stopped the train. Therefore, an engineer 15 can increase but cannot decrease brake pressure while running in a restricted block.

Limiting lugs 80 are provided on the outer faces of the pistons 13, 14 and 40 for preventing same from lapping or closing 20 their respective inlets 20, 22 and 39.

From the foregoing description, it will be seen that when the locomotive passes a danger signal into a charged restricted block, the solenoid of the conventional electro-pneumatic valve will be de-energized to permit exhaust of pressure in the high-pressure cylinder 13 through the pipe 20 and port 27 of the electro-pneumatic valve to the atmosphere. It might be here stated that normally one hundred and ten pounds pressure is maintained in both cylinders 13 and 14, but due to the larger diameter of the cylinder 13, the piston 15 holds the piston 16 and operating mechanism in the position shown 25 in full lines in the Figure 2. Upon such exhaust from the cylinder 13, the pressure in the cylinder 14 is sufficient to drive the piston 16 to the left and carry the piston 15 therewith. This movement rotates the 30 valve 24 through its geared connection with the rack bar, until the valve 24 closes the ports 22 and 23 to discontinue pressure and leave the piston 16 against the spring 31. During the said movement, ports 32 and 35 35 register to exhaust the ten pounds of equalizing reservoir pressure to effect the initial setting of brakes.

Coincident with said movement of the valve 24, the same opens the ports 37 and 38 to cause depression of the piston 41 to drop the key 43 out of alignment with the slots in the control handle to render the same inoperative to release the applied brake pressure. After said movement, the rotary 50 valve 24 opens the lead 56' to the split reduction governor 57, wherein pressure is detained for a period approximating that of manual split reduction, by means of the equalizing piston 60, and upon completion 55 of the automatic action thereof, said pressure from the pipe 56' will be fed through the pipe 30 to cause the second movement of the piston 16 against the spring and simultaneously rotate the depressed key 43, 60 release the pressure in the cylinder 40 and

effect the second or emergency brake application through the main rotary valve 52 in the usual well-known manner.

My improved device is applicable to any type of train control, but the particular type in which my improved device is shown employed, includes a reset contactor whereby the solenoid of the electro-pneumatic valve may be re-energized by manipulation of said reset contactor to reopen the lead from the main reservoir 10 to the high pressure cylinder to return the parts to normal position due to the larger volume of pressure which will overcome the pressure at this time remaining in the cylinder 14. The reset contactor mentioned is positioned at a point under the locomotive or tender, inaccessible to the engineer until the train has come to a complete stop, after which he must dismount to reset the relays which are adapted to open the circuit and keep the same open, after the train has entered a charged restricted block, until manually reset.

From the foregoing description, it is believed the construction and operation will be readily understood and that it will be seen I have provided a unit for automatic railway control systems embodying the feature, among others, of automatic means for governing split reduction for the application of brakes in a manner substantially universally adopted and manually effected in the present types of locomotives.

While I have described what I deem to be the most desirable embodiment of my invention, it is obvious that many of the details may be varied without in any way departing from the spirit of my invention, and I therefore do not limit myself to the exact details of construction herein set forth, nor to anything less than the whole of my invention limited only by the appended claims.

What is claimed as new is:

1. In an engineer's brake valve, a rotary valve for controlling the actuation of the air brakes of a train, a control handle operatively connected with said rotary valve for manually controlling the same, and automatic means for actuating said rotary valve independently of said control handle and for disconnecting said control handle from said rotary valve to prevent manual operation of said valve to a release position.

2. In an engineer's brake valve for controlling the application of the air brakes of a train, a rotary valve movable to a position to initially set the brakes and movable further to a final position to apply the brakes, a control handle operatively connected with said rotary valve for manually controlling the actuation of said rotary valve, and automatic means for actuating said rotary valve independently of said control handle for consecutively moving said rotary valve to its initial position and to said final position and

for disconnecting said control handle from said rotary valve to prevent manual operation of said rotary valve to a release position.

3. In an engineer's brake valve for controlling the application of the air brakes of a train on the split reduction principle, a rotary valve movable to a position to initially set the brakes and movable further to a final position to apply the brakes, a pair of cylinders normally containing an equal amount of pressure, rotary valve actuating means responsive to the pressure in said cylinders, automatic means for reducing the pressure from one cylinder to cause the pressure in the other cylinder to actuate said rotary valve actuating means to move said rotary valve to a position to set the brakes, and automatic means for increasing the pressure in said last mentioned cylinders in timed relation to the first actuation of said rotary valve for further actuating said rotary valve to move the same to said final position.

4. In combination with the main air reservoir and equalizer air reservoir of an air brake system, an engineer's brake valve including an equalizing piston interposed between a pair of chambers, each normally containing an equal amount of air pressure, a rotary valve, rotary valve actuating mechanism including a pair of cylinders normally containing an equal amount of air pressure approximating the air pressure in said main reservoir and said equalizer reservoir, automatic means for reducing the air pressure in one of said cylinders to cause the air pressure in said other cylinder to initially operate said valve actuating mechanism, means responsive to the initial movement of said rotary valve actuating mechanism for simultaneously exhausting a predetermined amount of air pressure from said equalizer reservoir and from one of said chambers to move said piston upwards, valve means controlled by upward movement of said piston for releasing a predetermined amount of air pressure from said last mentioned cylinder and from the other of said chambers to cause the pressure in said chambers to equalize to return said piston to normal position, and means for supplying main reservoir pressure to said last cylinder to further actuate said actuating mechanism to move said rotary valve to a final position substantially as and for the purpose specified.

5. In combination with the rotary control valve of an engineer's brake valve, a control handle, key means normally positioned to operatively connect said control handle with said rotary valve for manually operating the same, and automatic means for actuating said key means to render said control handle inoperative.

6. In combination with the rotary control valve of an engineer's brake valve, a control handle, key means normally positioned to operatively connect said control handle with said rotary valve for manually operating the same, and automatic means for actuating said key means to render said control handle inoperative, and automatic means operable upon the actuation of said first means for imparting rotation to said rotary valve.

7. In combination with the rotary valve of an engineer's brake valve, a control handle, a slidable key normally positioned between said rotary valve and said control handle for operatively connecting the same for manually operating said valve, and automatic means for sliding said key out of engagement with said control handle and into operative connection with said rotary valve.

8. In combination with the rotary valve of an engineer's brake valve, a control handle, a slidable key normally positioned between said rotary valve and said control handle for operatively connecting the same for manually operating said valve, and automatic means for sliding said key out of engagement with said control handle and into operative connection with said rotary valve, said means including a cylinder adapted to be supplied with compressed air, and a plunger connected with said key and slidable within said cylinder.

9. In combination with the rotary control valve of an engineer's brake valve, a control handle, key means normally positioned to operatively connect said control handle with said rotary valve for manually operating the same, automatic means for actuating said key means to render said control handle inoperative, automatic means operable upon the actuation of said first means for imparting rotation to said rotary valve, and automatic means operable upon the actuation of said first means for imparting a turning movement to said sliding key.

10. In combination with the rotary control valve of an engineer's brake valve, a control handle, key means normally positioned to operatively connect said control handle with said rotary valve for manually operating the same, automatic means for actuating said key means to render said control handle inoperative, automatic means operable upon the actuation of said first means for imparting rotation to said rotary valve, automatic means operable upon the actuation of said first means for imparting a turning movement to said sliding key, said last automatic means including a pair of spaced axially aligned cylinders normally containing an equal amount of air pressure, a piston in each of said cylinders, a rack bar connecting

said pistons, a gear fixed to said sliding key for co-action with said rack bar, and means for exhausting the air pressure in one of said cylinders and permitting the air pressure

5 in the other of said cylinders to cause move-

ment of said rack bar, substantially as and for the purpose specified.

In testimony whereof I affix my signature.

JOHN S. LONDON.
